BRAKE RIGGING WITH BEAM-RETRACTING SPRING

Frederic Schaefer, Pittsburgh, Pa.

Application November 15, 1947, Serial No. 786,234

5 Claims. (Cl. 188—213)

1

This invention relates to railway car brake rigging, and more particularly to means for insuring that the brake shoes will be held away from the wheels while the brakes are released.

It is among the objects of this invention to provide brake rigging in which the shoes will not drag against the wheels while the brakes are released, and in which this result is accomplished by springs of simple form connected to the beams and connecting rod in an improved manner.

In accordance with this invention a brake beam is pivotally connected to an operating lever that extends transversely of the beam. Spaced vertically from the beam is a substantially horizontal connecting rod that has one end pivotally connected to the lever in order to move the lever or to transmit motion from it to the other beam. A leaf spring is connected at its ends to the beam and rod and is formed for urging the beam toward the opposite end of the rod so that the spring will normally hold the brake shoes away from the wheels. Preferably, the connecting rod is hollow and one end of the spring extends into it, with the other end of the spring connected to a pin in the brake beam. It is highly desirable that this pin also connect one end of a beam-leveling link to the beam, the other end of the link being pivotally connected to the connecting rod. As a result, the brake beam is maintained level in all positions. The preferred embodiment of the invention is illustrated in the accompanying drawings in which Fig. 1 is a vertical transverse section through a car truck bolster and the associated brake beams, with part of the connecting rod and one of the beam struts broken away; and Fig. 2 is an enlarged view of the inner end of the spring, with the outline of the connecting rod shown in broken lines.

Referring to the drawings, a pair of brake beams, each formed from a channel-like compression member 1 and a tension rod 2 connected together at their ends by brake heads 3 and having their central portions spaced apart by a bifurcated strut 4, are suspended in the usual way from brake hangers 5 which support the brake heads. The beams are actuated to apply or release the brakes by means of operating levers 6 and 7 that have their lower ends pivotally connected in the struts by pins 8. The upper end of the dead lever 7 is held by a dead lever guide 9 projecting from one side of the truck bolster 11. The upper end of the live lever 6 is connected by a piston rod 12 with the usual brake cylinder (not shown).

Motion of the live lever is transmitted to the 55

2

dead lever through a connecting rod 13 having forked ends that straddle the levers. The body of the connecting rod is tubular, the rod preferably being like the one disclosed in my Patent No. 2,096,067. Each end of the rod is provided with two longitudinally spaced pairs of openings 14, in either pair of which a pin 16 may be disposed to pivotally connect the adjacent lever to the rod. Spaced inward from these openings at each end of the rod are two more longitudinally spaced pairs of openings 17 in either one of which a pivot pin 18 may be disposed for pivotally connecting the upper end of a beam-leveling link 19 to the rod. The lower end of the link is pivotally connected in the brake beam strut below it by means of a pin 21 adjacent channel 1. These links are of such length that they maintain the brake beams level and prevent them from tilting in a transverse vertical plane, whereby the upper ends of the brake shoes 22 are prevented from bearing against the wheels 23 with any more pressure than the lower ends of the shoes.

It is a feature of this invention that the brake beams are certain to be retracted far enough when the brakes are released to prevent the brake shoes from dragging against the wheels. Accordingly, a spring 26 is connected to each beam to swing it as far as possible toward the truck bolster. Each spring preferably is formed from a flat resilient bar which has been curved lengthwise. The lower end of the spring is bent into a loop to form an eye 27 that is inserted in a brake beam strut 4 and through which a pivot pin 21 extends. Because of this, the loop at the lower end of the adjoining leveling link 19 is made large enough to encircle the spring eye. This link loop is not entirely closed, so that the spring can extend out of it from pin 21. The spring is bowed toward the link with the upper end of the spring extending back into the hollow body of the connecting rod. This end of the spring extends downward in the rod and is provided with a concave end portion 28 which conforms somewhat to the transverse curvature of the rod and which also permits the spring to rock lengthwise of the rod. Due to the degree of curvature with which the body of the spring is provided initially, its opposite ends tend to move toward each other. When the beams are swung away from the bolster to apply the brakes, the struts carry the lower ends of the springs toward the wheels. This tends to straighten the springs, but, due to their resistance to being straightened, they swing the beams back toward the bolster as soon as the 50

brakes are released. This prevents the brake

shoes from dragging on the wheels while the brakes are not in applied position.

It will be noted that no extra fastening members are required for holding the springs in place because their upper ends are retained in the hollow brake rod while their lower ends are attached to the beam struts by the same pins that connect the leveling links to the struts. The springs also are of simple shape and easy to make, and due to their length they are not subjected to much flexing strain. Therefore, they have a long life.

According to the provisions of the patent statutes, I have explained the principle of my invention and have illustrated and described what I now consider to represent its best embodiment. However, I desire to have it understood that, within the scope of the appended claims, the invention may be practiced otherwise than as specifically illustrated and described.

I claim:

1. Railway car brake rigging comprising a brake beam, an operating lever extending transversely of the beam and pivotally connected to it, a substantially horizontal hollow connecting rod spaced vertically from the beam and having one end pivotally connected to the lever, and a leaf spring having one end disposed in said rod and the other end connected to the beam, and said spring being formed to urge the beam toward the opposite end of the rod to normally hold the beam in brake-released position.

2. Railway car brake rigging comprising a brake beam, an operating lever extending transversely of the beam and pivotally connected to it, a substantially horizontal hollow connecting rod spaced vertically from the beam and having one end pivotally connected to the lever, and a leaf spring having one end disposed in said rod and the other end connected to the beam, said spring being bowed toward said lever with the ends of the spring biased towards each other, whereby the spring urges the beam toward the rod to normally hold the beam in brake-released position.

3. Railway car brake rigging comprising a brake beam, an operating lever extending transversely of the beam and pivotally connected to it, a substantially horizontal hollow connecting rod spaced vertically from the beam and having one end pivotally connected to the lever, a beam-leveling link beside the lever, pivot pins connect-

ing the ends of the link to the beam and rod, and a leaf spring having one end connected to the pin that connects the link to the beam, the other end of the spring being disposed in said rod, said spring urging the beam toward the opposite end of the rod to normally hold the beam in brake-released position.

4. Railway car brake rigging comprising a brake beam, an operating lever extending transversely of the beam and pivotally connected to it, a substantially horizontal hollow connecting rod spaced vertically from the beam and having one end pivotally connected to the lever, a beam-leveling link beside the lever, pivot pins connecting the ends of the link to the beam and rod, and a leaf spring having one end disposed in said rod and the other end connected to the pin that connects the link to the beam, said spring being bowed toward said link with the ends of the spring biased towards each other, whereby the spring urges the beam toward the rod to normally hold the beam in brake-released position.

5. Railway car brake rigging comprising a brake beam, an operating lever extending transversely of the beam and pivotally connected to it, a substantially horizontal connecting rod spaced vertically from the beam and having one end pivotally connected to the lever, a leaf spring having one end connected to the rod and the other end provided with an eye, a pivot pin extending through said eye and connecting the spring to the beam, and a beam-leveling link beside the spring, having one end pivotally connected to the rod, the opposite end of the link encircling said spring eye to connect the link to the beam, and said spring being formed to urge the beam toward the opposite end of the rod to normally hold the beam in brake-released position.
